REFRIGERATOR CAR

Charles D. Bonsall, Pittsburgh, Pa., assignor, by
mesne assignments, to Standard Railway Equipment
Manufacturing Company, a corporation
of Delaware

Application November 22, 1937, Serial No. 175,761

8 Claims. (Cl. 62—16)

The invention relates to refrigerator cars for handling perishable commodities.

The objects of the invention are to provide a refrigerant container adaptable to hold solid refrigerants, such as wet ice, Dry Ice, or a liquid refrigerant, such as brine (salt water) and to form such refrigerant container and associate it with the other elements of a car so that the circulating refrigerating air may move below or around and also through the container and be cooled by the refrigerant, thus causing the air to circulate by convection through flues and channels provided for the purpose. Refrigerant containers, such as the usual brine tank, are now made with solid bottoms, tops and side walls so that the circulating air moves outside thereof and in contact therewith, but not in direct contact with the refrigerant. By allowing the circulating air to directly engage the refrigerant the heat transfer from the air to the refrigerant is greatly increased and the temperature of the circulating air is lowered, and the convection movement of the air is augmented, thus increasing the efficiency of the refrigerating system.

Another object is to provide an insulated partition or pan to catch the liquid refrigerant which splashes through the air circulating apertures in the tank and drains it into vertical air circulating flues in the wall of the car, from whence it is drained outside of the car, but which in the meantime further cools the air in the vertical flue.

A further object is to form or position the refrigerant container so that a liquid refrigerant therein will spill over the walls thereof at such a place that it must run over the pan to reach the side wall flue and thereby come in contact with the circulating air which it is passing under the refrigerant container to further cool the circulating air.

Another object is to position the air circulating apertures in the refrigerant tank so that the ventilating air entering the roof hatchway may move through as well as around the refrigerant tank.

In the drawing:

Fig. 1 is a partial cross section of a refrigerator car incorporating my invention.

Fig. 2 is a modification of the structure of Fig. 1.

One or more refrigerant containers 2 are preferably positioned on each side of the center line 4 of the car and adjacent the roof 6 of the car and also preferably adjacent the side or other vertical wall 8 of the car. The partition 10 is held in spaced relation to the side wall 8 by a series of vertical pieces to form the vertical flues 12. The

insulated horizontally disposed partition or drip pan 14 is positioned below the refrigerant container 2 and the space 16 is provided therebetween to form a substantially horizontal flue 16 which communicates with the vertical flue 12. A partition or member 18 extends upwardly from the inner margin of the horizontally disposed partition 14 and is spaced from the refrigerant container 2 to provide the short vertical flue 19. The vertically disposed members 18 on opposite sides 10 of the car are spaced apart to provide the air channel or flue 20. The usual refrigerant hatchway 22 and hinged closure 24 are shown. Also the usual foraminous false floor 26 (floor rack) supported in spaced relation to the floor 28 of the car by the stringers 30 to provide the flues 32. The lading rests upon the foraminous floor 26 and is usually placed so as to provide vertical flues between the component parts thereof.

In such a refrigerator car the refrigerant in the chambers 2 cools the air surrounding them so that, due to the increased weight and density, the air moves down the downwardly and outwardly inclined ceiling 14 (that is, in the flues 16 between the ceiling 14 and the refrigerant chamber 2) into the side wall vertical flues 12, and thence into the space 32 between the floor rack 26 and the floor 28 of the car, and then upwardly through openings in the floor rack 26 and between or through the lading, and being warmed thereby, rises and passes through the air channel 20 between the sloping ceilings 14—18 and thence around the refrigerant chamber 2, and being cooled thereby, repeats the cycle. Such cooling and heating of the air is continuously repeated. A further desirable feature of such construction is that the side wall flues 12 provide a blanket of cooled air around the lading and the water on the floor of the car also keeps the floor cold. Ice, salted ice, brine, Dry Ice or any of the usual refrigerants may be used in such a system. The arrows indicate air movement.

My improved refrigerant container or tank 2 is provided with a solid bottom 40 and the lower parts and side walls therefore are also solid or imperforate, while the upper parts 42 of the side walls are foraminous whereby the circulating air may come in direct contact with the refrigerant so as to increase the capacity of the device for cooling the circulating air. The lower parts of the side walls of the containers are solid so as to retain the brine within the tank so as to obtain the maximum heat absorbing capacity therefrom. This advantage would also be obtained from the melted ice when a solid ice is used. Experience

shows that a little brine left in the car while the car is being unloaded keeps the lading cool while being inspected and unloaded.

The upper edge 46 of the solid part of the container side 48 adjacent the car wall 8 is higher than the upper edge 50 of the opposite side 52 thereof. The ends of the container, (i. e., the walls of the container normal to the side walls 48 and 52) have the upper edges 54 of the solid parts thereof sloping downwardly away from the side wall 8 of the car. In such arrangement a liquid refrigerant (such as melted ice or brine) will spill over the edge of the solid parts furthest from the side wall 8 of the car and will pass over the horizontally disposed partition or pan 14 (i. e., in the substantially horizontal flue 16) thereby contacting the circulating air and further cooling it. Ice water will discharge from the container at slightly above 32° temperature and brine at even lower temperatures, either of which is colder than the circulating air. The upper edge 54 is preferably higher than the upper edge 50 of the container wall 52 to prevent liquid refrigerant from splashing out of the container.

The bottom solid wall 56 of the container 25 preferably slopes downwardly away from the wall 8 of the car (as shown in Fig. 1) to further cause the liquid refrigerant to spill over the edge 50 of the wall 52 of the container.

Fig. 2 shows a modified construction wherein the drip pan 14 slopes downwardly toward the side wall 8 (and communicates with the side wall flue 12) and the bottom 60 also slopes downwardly toward the side wall 8 (substantially parallel with the drip pan 14). The upper edge 61 of the solid part of the container side 62 adjacent the wall 8 is higher than the upper edge 63 of the opposite side 64 thereof so that the liquid refrigerant will spill over the edge 63 into the flue 16.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator, the combination of a vertical wall, a vertical flue associated with said wall, a refrigerant container adjacent said wall, and an insulated partition below said container and spaced therefrom to provide a substantially horizontal flue communicating with said vertical flue, the bottom and lower parts of the sides of said refrigerant container being solid with the upper parts of said sides being foraminous, the upper edge of the solid part of the container being furthest from said refrigerator wall being lower than the upper edge of the solid part of any other side thereof, whereby a liquid refrigerant in said container will spill over said lowest edge and pass through said horizontal flue.

2. In a refrigerator, the combination of a vertical wall, a vertical flue associated with said wall, a refrigerant container adjacent said wall, an insulated partition below said container and spaced therefrom to provide a substantially horizontal flue communicating with said vertical flue, and a member extending upwardly from the margin of said partition furthest from said wall, said member being in spaced relation to the refrigerant container, the bottom and lower parts of the sides of said refrigerant container being solid with the upper parts of said sides being foraminous, the upper edge of the solid part of the container side furthest from said refrigerator wall being lower than the upper edge of the solid part of any other wall thereof, whereby a liquid refrigerant in said container will spill over said lowest edge of the container and pass through said horizontal flue, the upper edge of said member being higher than the upper edge of the solid part of the container side furthest from said refrigerator wall.

3. In a refrigerator, the combination of a vertical wall, a vertical flue associated with said wall, a refrigerant container adjacent said wall, and an insulated partition below said container and spaced therefrom to provide a substantially horizontal flue communicating with said vertical flue, the bottom and the lower parts of the walls of said refrigerant container being solid, the upper edge of the solid part of the container side furthest from said refrigerator wall being lower than the upper edge of any other part thereof, whereby a liquid refrigerant in said container will spill over said lowest edge and pass through said horizontal flue.

4. A structure as defined in claim 3 wherein the insulated partition slopes downwardly toward said vertical flue.

5. A structure as defined in claim 3 wherein the bottom of the refrigerant container slopes downwardly away from said refrigerator wall.

6. A structure as defined in claim 3 wherein the insulated partition slopes downwardly toward said vertical flue and the bottom of the refrigerant container slopes downwardly away from said refrigerator wall.

7. A structure as defined in claim 3 wherein the insulated partition and the bottom of the refrigerant container slope downwardly toward said vertical flue.

8. In a refrigerator, the combination of a refrigerant container, a vertical wall, a vertical flue associated with said wall, and an insulated partition below said container and spaced therefrom to provide a substantially horizontal flue communicating with said vertical flue, the lower parts of said container being solid and the container side furthest from said refrigerator wall having apertures arranged so that a liquid refrigerant in said container will spill through said apertures and pass through said horizontal flue.

CHARLES D. BONSALL.
